(57) CLAIM

The ornamental design for a dishwashing/gardening glove,
as shown and described.

DESCRIPTION

FIG. 1 is a rear elevation view of a dishwashing/gardening glove showing a first embodiment of my new design;

FIG. 2 is a rear elevation view of a second embodiment
thereof;

FIG. 3 is a rear elevation view of a third embodiment
thereof;

FIG. 4 is a rear elevation view of a fourth embodiment
thereof;

FIG. 5 is a rear elevation view of a fifth embodiment thereof;

FIG. 6 is a rear elevation view of a sixth embodiment
thereof;

FIG. 7 is a rear elevation view of a seventh embodiment
thereof;

FIG. 8 is a front elevation view of a seventh embodiment
thereof;

FIG. 9 is a top and side perspective view of a seventh
embodiment thereof;

FIG. 10 is a rear elevation view of an eighth embodiment
thereof;

FIG. 11 is a front elevation view of an eighth embodiment thereof; and,

FIG. 12 is a top and side perspective view of an eighth
embodiment thereof.

Embodiments 1-6, FIGS. 1-6, are identical to embodiment 8, FIGS. 1-12, except that the gauntlet is of varying lengths.

The broken line showing of a partial arm is for illustrative purposes only and forms no part of the claimed design.
